[57] **CLAIM**

The ornamental design for a stapler base, as shown and described.

DESCRIPTION

FIG. 1 is a front elevational view of the stapler base showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is an isometric view thereof, the broken line showing of the stapler magazine cover and cap are shown for illustrative purposes only and form no part of the claimed design.

FIG. 1

FIG. 2

FIG. 3

FIG. 4
